UNITED STATES PATENT OFFICE.

EDWIN E. SLICK, OF PITTSBURG, PENNSYLVANIA.

ROLLING RAILS.

947,164.

Specification of Letters Patent. Patented Jan. 18, 1910.

Application filed May 16, 1906. Serial No. 317,081.

To all whom it may concern:

Be it known that I, EDWIN E. SLICK, of Pittsburgh, Allegheny county, Pennsylvania, have invented a new and useful Improvement in Rolling Rails, of which the following is a full, clear, and exact description, reference being had to the accompanying drawings, forming part of this specification, in which—

10 Figures 1 and 2 are side elevations of the roughing stands of rolls, and Figs. 3 and 4 are side elevations of the finishing stands of rolls having successive forming passes arranged in accordance with my invention.

15 In the methods heretofore used for rolling rails, it has been the practice to roll the blanks with the axis of the web of the rail always parallel or at right angles to the axes of the rolls and to form the comparatively 20 thin flange portions of the rail in the early stages of the rolling operation. The thin flange portions would lose their heat more rapidly and become colder than the larger and thicker head portion of the rail. This 25 would cause the density of the rails to vary in the head and flange portions, owing to their difference in temperature during the rolling operation. It has also been the practice heretofore to have a slabbing pass or 30 passes in which the vertical height of the shape being rolled is decreased. To accomplish this, it has been necessary to provide suitable turning devices for turning the material being rolled through an arc of 90 degrees so as to enter the successive passes in 35 suitable manner.

My invention relates to the rolling of rails and similar shapes, and the object of my invention is to provide means for rolling such 40 shapes without turning the blanks and in this way avoid the use of edging or slabbing passes and the turning devices usually employed in such mills.

A further object of my invention is to roll 45 a shape in such manner that the temperature in the different portions of the shape is kept more uniform while the rolling operation is being completed and in this way, produce a rail of uniform density and of an improved 50 quality.

In the drawings, Fig. 1 shows a three-high stand of rolls 2, 3 and 4. In this stand of rolls are duplicate passes a , a' and a^2 , and as shown, there is but one reducing pass a used although this number may be varied,

depending on the size of the blank from which the rail is rolled and the size of the finished rail, together with the arrangement and location of the stands of rolls comprising the mill. In this stand I start preferably with a bloom or billet, of substantially square cross section, which in passing through the first pass a is provided with a rudimentary head portion 5 and flange portions 6 and 7.

Fig. 2 shows the second three-high stand of rolls 8, 9 and 10 having the second pass b and third pass c in which passes the head portion 5, and flange portions 6 and 7 are further reduced and the web portion 11 is partly developed. It will be noted that the flange 6 in the first pass a is in the open live groove and the flange 7 is in the dead groove, while in the second pass b the flange 6 is in the dead groove and the flange 7 in the live groove. The blank is then passed through the third pass c in which the head and flange portions and the web portion are still further reduced, the flange 7 in this case being in the dead groove and the flange 6 in the live groove. The metal is then passed into the third set of rolls shown in Fig. 3. This is also a three-high stand of rolls 12, 13 and 14, which is provided with the fourth and fifth reducing passes d , e in which the shape is still further formed, the flange previously in the live groove now being in the dead groove and the one in the dead groove now being in the live groove. The metal is then passed into the fourth stand of rolls 15 which is shown as a two-high set of rolls having the finishing pass f , in which the flanges are bent to their final position and the rail is brought to its final shape.

It will be noted in this pass that the axis of the shape is parallel with the axes of the rolls and that a second duplicate pass f' is also shown. It will also be noted that in all of the reducing passes a line through the head and flange portions is at an angle to the axis of the rolls which is other than a right angle. This permits of the metal being reduced in height and width in one pass, and also avoids any possibility of buckling, as the sides of the different portions of the blank are always in contact with the faces of the pass at all times. Each of the several sets of rolls is provided with extra passes, the several passes in each set being duplicates of one another. The supplementary passes are for the 110

purpose of lengthening the time between the roll changes and for the purpose of increasing the life of the rolls.

The advantages of my invention will be apparent to those skilled in the art. By the absence of the usual slabbing and edging passes, the necessity of having mechanism for turning the blanks into position to enter the passes is avoided. The amount of reduction in the passes may be largely increased, and in this way the time required for reducing the blank is lessened and the output of the mill is increased. The flanges of the rail instead of being reduced to a comparatively thin cross section during the early stages of the reducing operation are kept shorter and thicker until the later reducing operations. In this way the flanges of the rails are finished at a much higher temperature than has heretofore been possible, and the density of the rail is rendered more uniform, resulting in an improved quality in the finished product.

Variations may be made in the number of passes employed, and instead of a plurality of stands of rolls with passes in each stand, they may be all arranged in the one set of rolls. The rails may be rolled with the flange portions normal to the web in each of the passes instead of as shown. The contour of the passes may be varied to suit the size and shape of the rail being rolled; and other changes may be made within the scope of my invention.

I claim:

1. The method of rolling T-head rails, consisting in passing a metal blank through a pass and dividing the blank into parts whose areas are substantially proportional to the area of the same parts in the finished rail, simultaneously reducing the parts in successive separate passes, in which the plane of the web is at an oblique angle to the axes of the rolls, passing the flange portions through alternate open live grooves and dead grooves, bending the flange portions out of their normal position and drawing out the metal to any width to which it will flow in the open live grooves, then passing such flange portion through a dead groove and then bending the flanges to their final position; substantially as described.

2. The method of rolling T-head rails consisting in passing a metal blank through a pass and dividing the blank into parts substantially proportional to the same parts in the finished rail, simultaneously reducing the head and flange portions in successive separate passes in which the plane of the web is at an oblique angle to the axes of the rolls, passing the flange portions alternately through an open live groove to bend the flange and draw out the metal to any width to which it will flow and then passing such flange through a dead groove and finally

bending the flanges to normal position; substantially as described.

3. The method of rolling T-head rails consisting in passing a metal blank through a pass and dividing the blank into parts whose areas are substantially proportional to those of the same parts in the finished rail, simultaneously reducing the parts in successive separate passes in which the plane of the web is at an oblique angle to the axes of the rolls, and the flange portions are bent out of their normal position, passing each flange portion alternately through an open live groove in which it is drawn out to any width to which the metal will flow and then through a dead groove, the flange portion in the dead groove in one pass being in the live groove in the next pass; substantially as described.

4. The method of rolling T-head rails consisting in passing a metal blank through a pass and dividing the blank into portions substantially proportional to the same parts in the finished rail, simultaneously reducing the parts in successive separate passes in which the plane of the web is at an angle to the axes of the rolls, passing the flange portions alternately through an open live groove and drawing out the flanges therein and then through a dead groove, the neutral axes through the head and flange portions being at an angle to the axes of the rolls in each pass which is less than ninety degrees; substantially as described.

5. The method of rolling T-head rails, consisting in passing the metal blank through a pass and dividing the blank into parts whose areas are substantially proportional to the same parts in the finished rail, simultaneously reducing the parts in successive separate passes in which the web is inclined in alternately opposite angles to the axes of the rolls, rolling the flange portions alternately within open live grooves, drawing out the flange in the open live groove to any width to which the metal will flow and then passing such flange through a dead groove; substantially as described.

6. The method of rolling T-head rails consisting in passing a metal blank of substantially rectangular cross section through a pass dividing the blank into parts substantially proportional to those of the same parts in the finished rail, then passing the blank through successive passes in which the web is inclined at alternately opposite angles to the axes of the rolls and simultaneously reducing the head and flange portions therein, rolling the flange portions alternately within open live grooves and dead grooves, bending the flange out of its normal position and drawing out the metal in the flange within the open live groove to any width to which the metal will flow and then passing such flange through a dead groove and then bending

ing the flanges to final position and finishing the rail; substantially as described.

7. The method of rolling T-head rails, consisting in passing a metal blank of substantially rectangular cross-section through a reducing pass and dividing it therein into unequal parts substantially proportional to the same parts of the finished rail, then passing the blank through successive passes in which its axis extending through the head and web is inclined at alternately opposite oblique angles to the axes of the rolls and simultaneously reducing the area of the head and flange portions therein, drawing out at least one of the flanges in the open live groove while bent out of its normal position to any width to which the metal will flow, then passing such flange portion through a dead groove and finally bending the flanges to final position; substantially as described.

8. The method of rolling T-head rails, consisting in passing a metal blank of substantially rectangular cross-section through a reducing pass and dividing the blank therein into unequal parts substantially proportional to the same parts in the finished rail, then passing the blank through successive passes in which its axis extending through the head and web is inclined at alternately opposite oblique angles to the axes of the rolls and simultaneously reducing the head and flange portions therein, drawing out at least one of the flanges to any width to which the metal flows in the open live groove while bent out of its normal position, then passing such flange portion through a dead groove and then bending the flange to its final position and supporting the web portion of the blank by contact with the rolls in each of the passes; substantially as described.

9. The method of rolling T-head rails consisting in passing a metal blank through a pass and dividing it into parts whose areas are substantially proportional to those of the same parts in the finished rail and simultaneously reducing the area of the head and flange parts in later passes while drawing out the flange portions in open live grooves extending at an oblique angle to the axes of the rolls in the later passes and then passing the blank through a finishing pass and finishing the section; substantially as described.

10. The method of rolling T-head rails, consisting in passing a metal blank through a reducing pass and dividing it into parts whose areas are substantially proportional to those of the same parts in the finished rail, then passing the blank through later passes and simultaneously reducing the area and width of the head portion and drawing out the flange portions in open live grooves forming part of the passes and extending at an oblique angle to the axes of the rolls in

the later passes, then passing the blank through a finishing pass and finishing the section; substantially as described.

11. The method of rolling rails, consisting in passing a metal blank through a reducing pass and dividing it into unequal parts whose areas are substantially proportional to those of the finished rail, simultaneously reducing the area of the parts in successive separate passes in which the axis extending through the head web and flange is at an oblique angle to the axes of the rolls and passing the flange portions through alternate live and dead grooves forming part of said passes, the live groove portions extending at an oblique angle to the axes of the rolls; substantially as described.

12. In a method of rolling T-head rails, the steps consisting in rolling the blank in reducing passes having flange portions extending at an oblique angle to the roll axes and thereby decreasing the width of the head and thickness of the flanges while maintaining the flange width of the blank being rolled; substantially as described.

13. In a method of rolling T-head rails, the steps consisting in rolling the blank in a series of reducing passes having the web and at least one flange portion extending at oblique angles to the roll axes and thereby maintaining the width of the flange while simultaneously decreasing the width of the head and thickness of the flange which extends at an oblique angle to the roll axes of the blank being rolled; substantially as described.

14. In a method of rolling T-head rails, the steps consisting in rolling the blank in a series of reducing passes having the web and at least one flange portion extending at oblique angles to the roll axes and thereby simultaneously decreasing the thickness of the flange which extends at an oblique angle to the roll axes, the web and the head portions, while maintaining the width of the flanges of the blank being rolled; substantially as described.

15. In a method of rolling T-head rails, the steps consisting in rolling the blank in a series of reducing passes having the web and at least one flange portion extending at oblique angles to the roll axes and thereby simultaneously decreasing the thickness of the head, the thickness of the flange extending at an oblique angle to the roll axes and the height of the section, while maintaining the width of the flanges of the blanks being rolled; substantially as described.

In testimony whereof, I have hereunto set my hand.

EDWIN E. SLICK.
